HANDBAG FRAME AND BAG

Leo Freidman, Bronx, N. Y., assignor to Gold Seal Importers, Inc., New York, N. Y., a corporation of New York

Application May 26, 1939, Serial No. 275,813

3 Claims. (Cl. 150—29)

The present invention relates to an improvement in handbag frames for use on ladies' and misses' handbags and the like.

The important structural feature of the present device lies in the provision, in a hinged closure frame for such bags, of an outstanding stitching flange whereby the outer portion of the bag and the lining thereof may be assembled on both sides of said flange and stitched thereto, preferably by hand, through perforations provided on said flange for this purpose.

The hinged frames may be made of any rigid material, such as metal of various kinds and finishes, or any of the various plastics found in the current market.

Frame connecting snap fasteners or clasps, not shown herein, of various types may be used, any desired form of ornamentation may also be used on these frames to enhance the appearance thereof.

The foregoing and other features of advantage will appear as the herein description proceeds, and it will be obvious that modifications may be made in the construction herein, without departing from the spirit hereof, or the scope of the appended claims.

In the drawing:

Fig. 1 is a view in elevation of the present improved frame;

Fig. 2 is a sectional view thereof, taken on line 2—2, Fig. 1, looking in the direction of the arrows;

Fig. 3 is a sectional, fragmentary view of a modified form of bag frame; and

Fig. 4 is an enlarged fragmentary, sectional view of the frame and its assembled outer bag and lining showing the mode of attaching the component parts, above noted, together.

The assembled frame, generally denoted by A, Figs. 1 and 2, comprises a pair of arcuate members, consisting of relatively wide, divergent, flat flanges 1 and 2, Fig. 2, the inner meeting ends of which are provided with integral, upstanding ledges 3 and 4. Each of the flanges are provided with a row of perforations 5 and 6, respectively, these perforations being spaced apart at desired distances, with the rows of perforations 5 and 6, in said flanges, running parallel with and adjacent to the ledges 3 and 4.

The two lower ends of each of the flanges 3 and 4 are developed into hinge forming extensions 7—11 and 9—10, respectively, Figs. 1 and 2, and these extensions on each frame are coupled together by pivot or hinge forming pins 8

and 12, so that the two hinged, component frames may be opened or closed, in the usual manner.

In Fig. 3 there is shown a frame structure that has a substantially similar structure to that described in Figs. 1 and 2, but the cross section shows the ledge 13 and the flange 14 as being either stamped or rolled up out of the sheet metal forming the frame or other available sheet material, this construction being provided with stitching apertures 15, which function is the same as the stitching apertures 5 and 6 in the flanges 1 and 2 of Figs. 1 and 2.

The opposed frame flanges 1 and 2 of Figs. 2 and 4, and the flange 14 of Fig. 3 lie in the same plane or planes to each other and the ledge forming elements 3—4 and 13—24 are located at right angles to the said flanges. As viewed in Figs. 2, 3 and 4, the flanges, at the mid-section of the frames at the section line 2—2, Fig. 1, are substantially horizontal and the ledges 3—4 and 13—24 are vertically located in relation to said flanges and this relation is maintained throughout the frame arcuate forming structures from hinge to hinge.

By the foregoing construction and with the wide flanges 21—22 and 14, the component outer bag envelope 16, Fig. 4 is so arranged that the bag is given a wide top formation W, Fig. 4, on its exterior, which creates an unusual, pleasing effect and makes a large fluffy top effect. This effect is amplified by shirring that portion of the outer bag top sewing edge 16, as indicated by the raised, or shirred portion 25, Fig. 4, which represents the raised flutes of the shirred bag edge portion. The shirring is closely formed all along the flange portions 21—22 or 14.

In attaching the outer cover of the bag and its liner 23 to the perforated flanges, the lining is first formed in the usual manner, and then, with its top edges overfolded, as at 23', thus forming a looped edge 20, the lining is then stitched through the apertures 5, Fig. 4, and when this is completed, the outer bag 16' is looped as at 16 by underfolding the opposed top edges of the outer bag 16' and then after shirring, as previously indicated, the outer bag is stitched through the apertures 5 to the frames, by stitches 18, such stitches being caught between the adjacent, contacting shirring elements 25, 45 to thus hide the stitches. Thus, the assembly of the outer bag 16' and the lining are completed. Other modified forms of stitching may be employed to accomplish the desired assembly of the outer bag and the lining to the frame A.

Having thus described the invention, what is claimed is:

1. A handbag comprising, in combination, frame members respectively comprising upstanding ledges provided at the outer ends with interconnecting hinge means; each frame member including a wide flat flange joining the inner edge of the ledge and extending in a direction away from the plane of the ledge perpendicularly thereto; each flange being provided with a series of perforations extending longitudinally of the flange near the ledge; a lining covering the inner face of the flange; stitches passing through said lining and perforations and in contact with the top face of the flange; an outer cover having its top margin infolded and disposed across the top face of the flange from edge to edge thereof between the cover and flange, and hiding said stitches and perforations, the fold being adjacent to the ledge; said cover being shirred over the flange to form raised portions, or flutes, extending across the flanges and down at the outer edges of the flanges; and stitches passed through said lining, said perforations, said infolded margin, and the shirred part between said flutes, the flutes hiding the last named stitches; said flanges being wide enough to give to the shirred portion a wide formation of shirring and a pleasing wide fluffy top effect; the outer edge of the flanges being far enough from the stitches to allow the shirring to curve over the outer edge without breaking the flutes.

2. A handbag comprising, in combination, a pair of one-piece U-shaped plate members bent to provide an inwardly opening channel part respectively forming upstanding ledges meeting in a single plane, the ledges being provided at the outer part of their end parts with overlapping hinge-ears perpendicular to said plane, and pivoted together to allow said ledges to pivot toward and from each other; each member including a flat flange integrally joining the inner edge of the ledge and extending in a direction away from said plane, perpendicularly thereto, a distance about four times the thickness of the ledge in said direction; each flange being provided with a series of perforations slightly spaced from the ledge; a lining having a part covering the inner face of the flange; stitches passing through said lining and perforations and holding the lining to the flange; an outer cover having its top margin infolded and disposed across the top face of the flange from edge to edge thereof between

the cover and flange, and hiding said stitches and perforations, the fold being adjacent to the ledge; said cover being closely shirred over the flange provide closely formed raised portions, or flutes, extending across the flanges and down at the outer edges; and stitches passed through said lining, said perforations, said infolded margin and the shirred part between said flutes, the flutes hiding the last named stitches.

3. In a handbag, the combination of a pair of one-piece U-shaped frame members of angular cross-section respectively comprising upstanding ledges meeting in a single plane and provided at the outer ends of their end edges with overlapping hinge-ears perpendicular to said plane, and pivoted together at said plane to allow said ledges to pivot toward and from each other; each frame member including a flat flange integrally joining the inner edge of the ledge and extending in a direction away from said plane, perpendicularly thereto, a distance about four times the thickness of the ledge in said direction; each flange being provided with a series of large perforations extending from end to end of the flange near and slightly spaced from the ledge; a lining having its top margin overfolded upon the lining and engaging the inner face of the flange from edge to edge thereof between the lining and flange, with the fold adjacent to the ledge and the free edge of the margin at the outer edge of the flange; stitches passing through said lining, margins and perforations and in contact with the top face of the flange between perforations; an outer cover having its top margin infolded and disposed across the top face of the flange from edge to edge thereof between the cover and flange, and hiding said stitches and perforations, the fold being adjacent to the ledge; said cover being shirred over the flange to form raised portions, or flutes, extending across the flanges and down at the outer edges of the flanges; and stitches passed through said lining, its margin, said perforations, said infolded margin and the shirred part between said flutes, and flutes hiding the last named stitches; said flanges being wide enough to give to the shirred portion a wide formation of shirring and a pleasing wide fluffy top effect; the outer edge of the flanges being far enough from the stitches to allow the shirring to curve over the outer edge without breaking the flutes.

LEO FREIDMAN.
